UNITED STATES PATENT OFFICE

FRANK T. COPE, ARTHUR H. VAUGHAN, AND WILBUR S. BOWLING, OF SALEM, OHIO,
ASSIGNORS TO THE ELECTRIC FURNACE COMPANY, OF SALEM, OHIO, A CORPORA-
TION OF OHIO

ROTARY HEAT TREATING FURNACE

Application filed April 30, 1930. Serial No. 448,609.

The invention relates to apparatus for heat treating metal articles in the presence of gas, and more particularly to surface hardening of steel in the presence of ammonia, which is commonly known as nitriding, although from the following description it will be evident that other heat treatments, such as gas carburizing, annealing and the like may be advantageously carried on in the furnaces embodying the invention.

It is usual practice in nitriding to heat the steel objects to be treated, in a closed container, in the presence of ammonia gas, at a temperature usually between 900° F. and 1200° F., for a period depending upon the depth of nitrogen penetration desired. A small quantity of ammonia gas is caused to flow continuously into the container, and the spent gas is allowed to escape through a suitable outlet.

Heretofore it has been customary to use a furnace of the so called "batch" type. However, it is obvious that some form of continuous furnace is more desirable, because of the time necessarily lost in unloading and reloading the container, the inconvenience of moving the container in and out of the furnace, the difficulty of duplicating temperature conditions from charge to charge, and the excessive amount of attendance required in the use of a "batch" type furnace.

An object of the improvement is to provide a furnace for heating objects in containers wherein a plurality of separate charges, each in a container, are at a given time at successive stages of the treatment.

Another object is to provide convenient means for conveying the work-carrying containers through the furnace chamber.

A further object is to provide means for maintaining a continuous supply of gas to the containers, regardless of their movement within or without the furnace chamber; and to provide for preventing the entrance of air to the containers, except as desired.

A still further object of the improvement is to so construct the furnace that the containers may be loaded and unloaded while in

a convenient position, and with a minimum of difficulty.

Still another object is the provision of means for conveying the containers from which the entire containers need not be removed at any stage of the heat treatment.

Another object is to provide means for cooling the containers outside of the furnace chamber to a temperature at which they may be unloaded and reloaded.

The above, together with other objects which will be apparent from the following detailed description of the invention, may be attained by providing a partially circular or discontinuous annular heating chamber with radially disposed entrance and exit doors at opposite sides, an annular, rotary hearth being concentrically mounted in the lower portion of the heating chamber and having an acute portion at all times extended outside of the heating chamber between said doors; containers, for the objects to be heat treated, being carried upon the hearth, and provided with removable covers adapted to be removed and replaced for unloading and reloading the material as the containers move to a point outside of the heating chamber; means being provided for continuously circulating gas through the containers while the hearth is in motion; and sealing means being provided for the hearth and for the containers, whereby air is prevented from entering the furnace and containers.

An embodiment of the invention thus briefly described is illustrated in the accompanying drawings, in which

Figure 1 is a vertical sectional view of a preferred form of the improved furnace, taken substantially on the line 1-1, Fig. 2;

Fig. 2, a plan section taken as on the line 2-2, Fig. 1;

Fig. 3, a section, similar to Fig. 1, of a modified form of furnace, having a single sealing means for the hearth and containers, taken substantially on the line 3-3, Fig. 4; and

Fig. 4, a plan section of the modified form of furnace, taken on the line 4-4, Fig. 3.

Similar numerals refer to similar parts throughout the drawings.

Referring first to the form of the apparatus illustrated in Figs. 1 and 2, the furnace chamber is partially circular and provided with the arcuate outer wall 10 and 5 concentric inner wall 11, joined at their upper extremities by the partly annular roof 12, and supported upon a suitable structural frame comprising the base 13, the uprights 14 and the beams 15. As shown in 10 Fig. 2, the lower extremities of the outer and inner walls are continued between the charging and discharging doors C and D, respectively, as indicated at 10a and 11a, respectively.

15 A bearing 16, which may be in the form of a ball bearing as shown in Fig. 1, is mounted upon the base 13, concentric with the furnace chamber, and rotatably supports the hub 17, to which are attached the 20 spokes 18 carrying the frame 19, upon which is mounted an annular casting 20.

25 A ring gear 21 is formed around the periphery of the casting 20, and meshes with the pinion 22, mounted upon a vertical shaft 23 and driven through the gear reduction 24 which is operatively connected to the motor 25 as by the coupling 27, the entire driving means being mounted upon a frame 28 carried by the base 13.

30 The casting 20 carries the refractory hearth 29 which is located between the lower ends of the outer and inner walls 10 and 11, respectively, of the furnace chamber.

35 For the purpose of sealing the furnace chamber from the outside atmosphere, spaced annular channels or troughs 30 and 31 are formed upon the casting 20, and adapted to contain suitable sealing material which may be a liquid or a granular material; depending annular flanges 32 and 33 being carried by the inner and outer walls respectively, and extended into said channels 30 and 31 respectively.

40 Each of the containers for the objects to be treated includes a bottom plate 34 mounted upon the hearth 29 and having a peripheral sealing trough 35 adapted to contain suitable sealing material.

45 A depending bearing portion 36 is preferably formed upon each plate 34 and provided with a stuffing box 37, a vertical shaft 38 being journaled therethrough and provided with a fan or propeller 39 at its upper end.

50 This fan shaft has a pulley 40 on its lower end, operatively connected, as by the belt 41, with a similar pulley 42 upon the shaft of a motor 43, suitably supported upon the rotating frame 19. One of these motors 55 may be provided for driving the fan of each of the containers.

55 The container has therein a hollow cylinder 44, forming a work supporting receptacle and circulation directing baffle, open 60 at both ends, and having the reduced neck

45 at its lower end, into the mouth of which the fan 39 is located.

Legs 46 may be provided for supporting these cylinders spaced above the bottom plates 34, and the objects to be heat treated 70 may be placed upon the grating or mesh shelves 47, located in spaced relation within the cylinders as by the brackets 48.

75 Each container comprises the bottom plate 34 and a removable, inverted cover 49, spaced from the sides and upper end of the cylinder 44, and having its lower open end seated within the sealing channel 35 of the bottom plate.

80 In order to firmly hold the cover in place around the cylinder during the heat treating operation, ears 50 may be provided upon the outside thereof, near the lower edge of the cover, for cooperation with the ears 51 upon the outer flange of the sealing channel 85 35, pins 52 being adapted to be located through suitable registering openings in the ears.

85 The furnace chamber may be heated by any suitable and well known means, and for 90 the purpose of illustration electric heating elements 53 are shown upon the walls 10 and 11 thereof.

95 A central, vertical shaft 54, which may be tubular as shown in the drawings, is carried by the hub 17, and extends upward through the tubular casing 55, located 100 through the center of the furnace. The casing 55 is attached at its upper end to the beams 15 and at its lower end to the base plate 15a and serves to support and locate the inner wall 11.

105 For the purpose of providing a hydraulic sealing chamber, and to permit the use of a slightly elevated pressure within the container, a cylindric receptacle 56 is fixed to the upper end of the shaft 54 and adapted to contain any suitable liquid. A sealing plate 57 is fixed above the receptacle 56, being supported as upon the uprights 58 mounted on the beam members 15 and is provided with the inner and outer spaced annular flanges 59 and 60 respectively, concentric with the shaft 54 and extending into the liquid in the receptacle 56.

110 Gas for the heat treatment is admitted within the center chamber 61 of the gas sealing receptacle through the pipe 62 and passes from the chamber 61 into the central pipe 63, carried by the receptacle 56 and then through the radial passage 64 in the bottom of said receptacle to the gas inlet pipe 65 which extends downward alongside of the shaft 54 and then outward at an angle, communicating with the circumferentially disposed inlet 115 manifold 66.

120 Inlet pipes 67 lead from the manifold 66 to the interior of each container, terminating just below the fan 39 of the container so that the gas discharged therefrom is carried up- 125

ward by the fan, through the container and around the objects under treatment.

The gas then passes downward between the container proper and the cover 49 thereof and a portion flows into the corresponding discharge pipe 68, these discharge pipes being connected to the circumferentially disposed outlet manifold 69.

For the purpose of controlling the flow of gas through any particular container, valves 70 and 71 may be provided in the pipes 67 and 68 respectively. The spent gas from the outlet manifold passes upward through the discharge pipe 72 and into the annular chamber 73 of the sealing receptacle, being discharged through the pipe 74 which extends through the stationary top plate 57 of the receptacle. The pipe 74 may extend to a point remote from the furnace if desired, and may be provided with means for maintaining back pressure and preventing the entrance of air. Such means may consist of a liquid seal or a throttling valve 81.

The gas supply pipes as well as the discharge pipes for the spent gas are thus connected to the hydraulically sealed swivel connection which permits relative movement of the parts without disturbing the flow of the gas in either direction.

For the purpose of carrying current to the motors 43 and the heating elements 53, a plurality of annular conductors 75 may be carried upon an insulation ring 76 fixed upon the periphery of the rotating receptacle 56, these conductors being connected by any suitable wiring which may be located through the conduit 80 and connected to the various motors and heating elements. The conductors 75 contact with the shoes 77 to which suitable line wires may be connected.

In the operation of the apparatus for nitriding or other treatment involving the use of a gas, the hearth may preferably be rotated intermittently in the direction of the arrow shown on Fig. 2, the doors C and D being opened at intervals to permit the containers to pass in and out of the heating chamber.

As each container passes out of the heating chamber, it may be allowed to cool to a temperature at which it may be opened, gas continuing to flow meanwhile if desired, after which the container may be opened, unloaded, and filled with new material to be treated and again passed through the furnace chamber.

As above described, it will be obvious that each container is separately sealed from the atmosphere, preventing the entrance of air into the container except when desired and suitable gas for the treatment may be continuously circulated through each container while the same is at a temperature requiring the presence of the gas.

It will also be seen that the rate of flow of

the gas through each container may be independently regulated so as to produce the desired results in the heat treating operation.

In Figs. 3 and 4 is illustrated a modified form of furnace in which the containers and hearth are sealed by a single sealing means. Otherwise the general structure of this furnace is very similar to that above described, as will be evident from an inspection of the drawings and the following detailed description of this modified form of the invention.

In this form of the furnace the furnace chamber is also partially circular and provided with the arcuate outer and inner walls 10' and 11' respectively, joined at their upper ends by the partly annular roof 12' and supported upon the structural frame comprising the base 13', uprights 14' and beam members 15'.

As shown in Fig. 4, the lower portions of the outer and inner walls are continued throughout the cut-out portion between opposite ends of the furnace chamber, as shown at 10" and 11", respectively.

The bearing 16' is mounted upon the base, concentric with the furnace chamber and rotatably supports the hub 17' carrying the spokes 18' and rotatable frame 19' upon which is mounted the annular casting 20'.

A ring gear 21' may be formed around the periphery of the casting and engaged by the pinion 22' upon the vertical shaft 23' driven through the gear reduction 24' operatively connected to the motor 25' as by the coupling 27'.

The rotatable casting 20' is provided at its outer and inner edges with the annular sealing channels 30' and 31' respectively, adapted to contain suitable sealing material and receiving the depending annular flanges 32' and 33' depending from the lower ends of the outer and inner walls respectively.

A plurality of circular channels 35', corresponding in number and position to the containers to be carried upon the hearth, are formed in the casting 20' and communicate with the channels 30' and 31' so as to receive the sealing material which may preferably be oil in this case.

A vertical bearing 36' is centrally located through the refractory hearth block 29' of each container and may be provided with a stuffing box 37', a fan shaft 38' being journaled therethrough and provided at its upper end with a fan or propeller 39'. A motor 43' is carried by the rotatable frame 19' for driving each fan shaft.

Each container may have therein a work-supporting receptacle in the form of a hollow cylinder 44' open at both ends and having the reduced neck 45' at its lower end, the fan 39' being located in the mouth thereof.

Legs 46' may be provided for supporting each receptacle 44' spaced above the hearth block 29' and the objects to be treated may

be placed upon the shelves 47' located in spaced relation within the receptacles upon the brackets 48'.

Each container proper includes, in combination with the cooperating portion of the hearth casting 20', an inverted removable cover 49' which extends downward around the circular hearth block 29' and into the corresponding circular sealing channel 35'.

- 10 An inner annular flange 49'' may be provided upon each cover for resting upon the corresponding hearth block 29' to properly position the cover over the receptacle 44' and a similar flange 49''' may be located around 70 the periphery of the receptacle and slightly spaced above the inturned projections of the inner and outer furnace walls, as best shown in Fig. 3.

The furnace chamber may be heated by 20 any suitable means such as the electric heating elements 53' located upon the inner and outer walls of the furnace chamber. Refractory blocks of the shape best shown at 51' in Fig. 4 are located upon the casting 20' 25 between the circular hearth blocks 29' which support the containers.

A central vertical shaft 54', which may be tubular as shown in the drawings, is carried by the hub 17' and extends upward through 30 the tubular casing 55' located through the center of the furnace. The casing 55' is attached at its upper end to the beams 15' and at its lower end to the base plate 15a', and serves to support and locate the inner wall 35 11'.

For the purpose of providing a hydraulic sealing chamber and to permit the use of a slightly elevated pressure within the container, a cylindric container 56' is carried 40 by the upper end of the shaft 54' and adapted to contain any suitable liquid. A sealing plate 57' is fixed above the receptacle 56', being supported as upon the uprights 58' mounted on the beam members 15' and is provided with the inner and outer spaced annular flanges 59' and 60', respectively, concentric with the shaft 54' and extending into the liquid in the receptacle 56'.

Gas for the heat treatment is admitted 50 within the center chamber 61' of the gas sealing receptacle through the pipe 62' and passes from the chamber 61' into the central pipe 63', carried by the receptacle 56' and then through the radial passage 64' in 55 the bottom of said receptacle to the gas inlet pipe 65' which extends downward alongside of the shaft 54' and then outward at an angle, communicating with the inlet manifold 66'.

60 Inlet pipes 67' lead from the manifold 66' to the interior of each container, terminating just below the fan 39' of the container so that the gas discharged therefrom is carried upward by the fan, through the container 65 and around the objects under treatment.

The gas then passes downward between the container proper and the cover 49' thereof and a portion flows into the corresponding discharge pipe 68', these discharge pipes being connected to the outlet manifold 69'. 70

For the purpose of controlling the flow of gas through any particular container, valves 70' and 71' may be provided in the pipes 67' and 68', respectively. The spent gas from the outlet manifold passes upward 75 through the discharge pipe 72' and into the annular chamber 73' of the sealing receptacle, being discharged through the pipe 74' which extends through the stationary top plate 57' of the receptacle. The pipe 74' 80 may extend to a point remote from the furnace, if desired, and may be provided with means for maintaining back pressure and preventing the entrance of air. Such means 85 may consist of a liquid seal or a throttling valve.

For the purpose of carrying current to the motors 43' and the heating elements 53', a plurality of annular conductors 75' may be carried upon an insulation ring 76' fixed upon the periphery of the rotating receptacle 56', these conductors being connected by any suitable wiring which may be located through the conduit 80', and connected to the various motors and heating elements and contacting with the shoes 77' to which suitable line wires may be connected. 90

Although circulating means are shown in the drawings, in the form of fans for continuously circulating gas through the containers during the heat treating operation, it should be understood that such circulating means are not necessary in all cases, and may be omitted within the scope of the invention. 100

We claim:

1. A furnace having a discontinuous, annular chamber, a continuous, annular, rotatable hearth located concentric with said chamber and forming the bottom thereof, a closed container supported by said hearth, a hollow work-supporting receptacle within the container, open at its upper end and spaced from the sides and top of the container, and means for admitting gas to the lower end of said work-supporting receptacle and withdrawing gas from the container at a point outside of the work-supporting receptacle. 110

2. A furnace having a discontinuous, annular chamber, a continuous, annular, rotatable hearth located concentric with said chamber and forming the bottom thereof, a closed container supported by said hearth, a hollow work-supporting receptacle within the container open at its upper end and spaced from the sides and top of the container, and means for circulating gas in one direction through said hollow work-support 115 120 125 130

and in the opposite direction between the work-support and the sides of the container.

3. A furnace having a discontinuous, annular chamber, a continuous, annular, rotatable hearth located concentric with said chamber and forming the bottom thereof, a closed, work-carrying container supported by said hearth, a pipe for supplying gas to said container, a second pipe for carrying away spent gas from said container, said pipes rotating with the hearth, a sealed swivel connection associated with said pipes, fixed pipes connected with said swivel connection, and means for maintaining a positive gas pressure within said container, said means being associated with the pipe for carrying away spent gas and being located beyond said swivel connection.

4. A furnace having a discontinuous, annular chamber, a continuous, annular, rotatable hearth located concentric with said chamber and forming the bottom thereof, a plurality of spaced, separately closed, work-carrying containers supported by said hearth, a pipe for supplying gas to each container, a second pipe for carrying away spent gas from each container, said pipes rotating with the hearth, a hydraulically sealed swivel connection associated with said pipes, pipes connected with said swivel connection, and means for maintaining a positive gas pressure within said container.

5. A furnace having a discontinuous, annular chamber, a continuous, annular, rotatable hearth located concentric with said chamber and forming the bottom thereof, a plurality of spaced, separately closed, work-carrying containers supported by said hearth, a pipe for supplying gas to each container, a second pipe for carrying away spent gas from each container, said pipes rotating with the hearth, a hydraulically sealed swivel connection associated with said pipes, pipes connected with said swivel connection, and means for maintaining a positive gas pressure within said container, said means being associated with the pipe for carrying away spent gas and being located beyond said swivel connection.

6. A furnace having a discontinuous, annular chamber, a continuous annular rotatable hearth located concentric with said chamber and forming the bottom thereof, a closed container supported by said hearth, a hollow work-supporting receptacle within the container, open at its upper end and spaced from the sides and top of the container, and means for admitting gas to said work-supporting receptacle and withdrawing gas from the container.

7. A furnace having a discontinuous, annular chamber, a continuous, annular, rotatable hearth located concentric with said chamber and forming the bottom thereof, a plurality of spaced separately closed work-

carrying containers supported by said hearth, a circumferentially disposed inlet pipe rotating with said hearth, and a separate connection between the inlet pipe and each container.

8. A furnace having a discontinuous, annular chamber, a continuous, annular, rotatable hearth located concentric with said chamber and forming the bottom thereof, a plurality of spaced separately closed work-carrying containers supported by said hearth, a circumferentially disposed inlet pipe rotating with said hearth, a circumferentially disposed outlet pipe rotating with said hearth, and separate connections between the inlet and outlet pipes and each container.

9. A furnace having a discontinuous, annular chamber, a continuous, annular, rotatable hearth located concentric with said chamber and forming the bottom thereof, a plurality of spaced separately closed work-carrying containers supported by said hearth, an inlet pipe rotating with said hearth and having a circumferentially disposed portion, an outlet pipe rotating with said hearth and having a circumferentially disposed portion, separate connections between the circumferentially disposed portions of the inlet and outlet pipes and each container, a sealed swivel connection associated with the inlet and outlet pipes, and fixed pipes connected with the swivel connection.

In testimony that we claim the above, we have hereunto subscribed our names.
